FIG. 1 is a top plan view of a toilet tank cover showing my new design;

FIG. 2 is a left side elevational view thereof;

FIG. 3 is a right side elevational view thereof; and
FIG. 4 is a front elevational view thereof.

This is a divisional of design application Ser. No. D. 20,960, filed Jan. 16, 1970, now abandoned.

The characteristic feature of my design resides in the graining striations extending from the corner of one side of the top of the cover across the top of the cover to the diagonally opposite sides of the cover.

I claim:

The ornamental design for a toilet tank cover, as shown and described.
